UNITED STATES PATENT OFFICE.

CHARLES ERWIN NORMAN, OF CHICAGO, ILLINOIS.

HOT-BLAST FURNACE.

1,079,432.

Specification of Letters Patent. Patented Nov. 25, 1913.

Application filed May 18, 1910. Serial No. 561,851.

To all whom it may concern:

Be it known that I, CHARLES E. NORMAN, a citizen of the United States, residing at Chicago, in the county of Cook and State of Illinois, have invented a certain new and useful Improvement in Hot-Blast Furnaces, of which the following is a specification.

My invention relates to improvements in hot blast furnaces and has for its object to 10 provide a hot blast in the combustion chamber independently of the fire.

It is illustrated in the accompanying drawings wherein—

Figure 1 is a section; Fig. 2, a section 15 along the line 2—2 of Fig. 1; Fig. 3, a section along the line 3—3 of Fig. 1; Fig. 4, a rear elevation; Fig. 5, a detail of the heating device.

Like letters refer to like parts throughout 20 the several figures.

The grate A is located within the furnace base A¹, having above it the combustion chamber A² and below it the ash chamber A³. The boiler B is located above the grate A¹ and surrounds the combustion chamber A². The steam dome B¹ is connected by means of the passage B² with the boiler B and is supported by the casing B³ which surrounds the boiler B and is carried by the base A¹. The partition B⁴ between the boiler B and casing B³ forms the smoke box B⁵ which communicates with the combustion chamber A² by means of the passage B⁶. The passage B⁶ leads from the smoke box B⁵ through the steam dome B¹ to the smoke pipe B⁸ in which is located the check draft opening B⁹ controlled by the damper B¹⁰. The air chamber C having the damper C¹ mounted upon the rod C² communicates with 40 the ash box A³ by means of the opening C³ and is connected by means of the pipes C⁴ with the annular chamber C⁵ between the boiler B and casing B⁴. The passages C⁶ connect the chamber C⁵ with the combustion chamber A² at a point above the grate. The pipes D which are located within the pipes C⁴ and held centrally therein by means of the radially projecting flanges D¹, have near their bases the openings D² and are closed 50 at their lower ends by the plugs D³ having therethrough the passages D⁴ in communication with the gas pipe D⁶ and adapted to be controlled by the turn cock D⁷ rigidly carried by the rod C². The pilot light D⁷ is located at the base of each pipe D and 55 communicates with the gas pipe D⁶ by

means of the pipe D⁸, and is controlled by the valve D⁹. The pipe E leads from the steam dome B¹ to the T E¹ from which leads the pipe E² to the pressure gage E³ and the pipe E⁴ to the usual receptacle E⁵ in which is the usual steam diaphragm not shown, carrying the piston E⁶ to move the lever arm E⁷ upon which is mounted the adjustable weight E⁸. The chain E⁹ leads from the lever arm E⁷ to the damper B¹⁰. The chain E¹⁰ leads from the lever arm E⁷ over the pulleys E¹¹ to the damper C¹, the two chains being so arranged that when the damper B¹⁰ is open, owing to the pressure 70 of the steam upon the diaphragm overcom- ing the weight E⁸, the damper C¹ is closed and vice versa.

It will be evident that while I have shown in my drawings an operative device, still 75 many changes might be made both in size, shape and arrangement of parts without departing materially from the spirit of my invention.

In hot blast furnaces, it has been cus- 80 tomary to deliver a supply of hot air to the combustion chamber above the grate. This supply of air, however, has always been heated by the fire in the grate. The object of this hot blast is to prevent the precipita- 85 tion of free carbon owing to the influx of the supply of cold air above the grate. It has been found, however, that the greatest smoking occurs when the fire is first started, at which time the hot blast is not a hot blast, but a cold blast, since the fire in the grate 90 has not heated up the apparatus sufficiently to cause the air to be heated and a great deal of smoking therefore occurs.

In my invention I provide means for 95 heating the blast of air to the combustion chamber quite independent of the fire in the grate and in this manner I am able to deliver a blast of hot air to the combustion chamber at the time when it is most needed, 100 that is, when the fire has just been started. This I do automatically by providing an air chamber controlled by a damper responsive to the steam pressure or other means, a connection from such air chamber to the combustion chamber and heating means within such connection, said heating means rendered automatically operative by the operation of the damper. Thus when the damper 105 is open, the heating means are turned on and 110 the air is heated and when the damper is closed, owing to the too great increase of

pressure in the steam boiler or for other reasons, the heating means are disconnected or turned off and the blast is heated by the heat of the fire alone.

5 I have illustrated this device in connection with coal burning steam heating plant and I have heated my blast by means of a gas heater, which is provided with a pilot light which is at all times burning, although the 10 main burners are lighted only when needed. It will be evident that this device would be applicable to a furnace heated by other means such as gas or oil and it will be evident that a blast might be heated by gas, 15 oil or electricity or any other suitable means.

I claim:

1. The combination with a furnace, of means for supplying air to the combustion chamber together with means for heating 20 said air independently of the furnace, said means comprising a pipe and a damper, and heating means within said pipe, said heating means being operative responsive to the operation of said damper.

25 2. The combination with a furnace having a combustion chamber and ash box of an air chamber in communication with the ash box, a damper controlling the air supply to said air chamber, a smoke flue and check 30 damper therein, a passage outside of the furnace leading from the air chamber to the combustion chamber, heating means within such passage for the air as it passes to the combustion chamber, said means operative 35 only when the damper in such air chamber is open.

3. The combination with a furnace having a combustion chamber and an ash box of an air chamber in communication with the ash 40 box, means for controlling the supply of air to said air chamber, a smoke flue and check damper therein, a passage outside of the furnace leading from the air chamber to the combustion chamber, heating means within 45 such passage for the air as it passes to the combustion chamber, said means operative only when air is being supplied to said air chamber.

4. The combination with a furnace having a combustion chamber and an ash box of an 50 air chamber in communication with the ash box, means for controlling the supply of air to said air chamber, said means comprising a damper, a smoke flue and check damper 55 therein, a passage outside of the furnace leading from the air chamber to the combustion chamber, heating means within such passage for the air as it passes to the combustion chamber, said means operative only when air is being supplied to said air chamber.

5. The combination with a furnace having a combustion chamber and an ash box of an air chamber in communication with the ash 65 box, means for controlling the supply of air to said air chamber comprising a damper in said chamber, a smoke flue and check damper 70 therein, a passage outside of the furnace leading from the air chamber to the combustion chamber, and heating means within such passage for the air as it passes to the combustion chamber, said means operative only when the damper in such air chamber is open.

6. The combination with a furnace of 75 means for supplying air to the combustion chamber above the grate, means for heating such air when the furnace is cold, and means responsive to conditions in the furnace for discontinuing said heating means when the 80 temperature in the furnace reaches a certain predetermined point.

7. The combination with a furnace of means for supplying air to the combustion chamber above the grate together with 85 means for heating such air and means responsive to conditions in the furnace for progressively interrupting the supply of heating medium as the heat in the furnace increases beyond a certain predetermined 90 point.
